DANIEL E. CONKLIN, OF BALTIMORE, MARYLAND, ASSIGNOR TO HARBECK, CONKLIN, AND WILLIS, OF SAME PLACE.

Design No. 3,532, dated June 8, 1869.

DESIGN FOR A COOK'S STOVE.

The Schedule referred to in these Letters Patent and making part of the same.

To all whom it may concern:

Be it known that I, DANIEL E. CONKLIN, of the city of Baltimore, in the State of Maryland, have invented a new Design for a Cooking-Stove; and I hereby declare that the same is correctly represented in the accompanying drawing, which forms a part of this specification.

There is not necessarily any peculiarity in the mechanical construction of my stove. It is an ordinary diving-flue high-hearth cooking-stove, made of various numbers or sizes, and adapted for burning either wood or coal. Any suitable arrangement of flues may be employed, and no novelty is claimed in such arrangement.

The essential features of my design are, first, the Virginia State coat of arms on the side doors, with the words "Sic semper tyraunis;" and secondly, the name "Stonewall," which is applied above the said doors, or in other convenient place.

I claim as new, and desire to secure by Letters Patent—

The design for a cooking-stove, substantially as herein set forth.

DANIEL E. CONKLIN.
